US0D1012614S

(12) **United States Design Patent** (10) **Patent No.:** **US D1,012,614 S**
(45) **Date of Patent:** **** Jan. 30, 2024**

(54) **CUP**

(71) Applicant: **Xuanjun Cai**, Chaozhou (CN)

(72) Inventor: **Xuanjun Cai**, Chaozhou (CN)

(**) Term: **15 Years**

(21) Appl. No.: **29/765,753**

(22) Filed: **Jan. 11, 2021**

(51) LOC (14) Cl. **07-01**

(52) U.S. Cl.

USPC **D7/507**; D7/533

(58) **Field of Classification Search**

USPC D7/394, 507, 509, 510, 511, 529, 532, D7/533, 536, 537, 538, 543, 602;

D9/716

CPC . A47J 31/02; A47J 31/14; A47J 31/20; A47G 19/14; A47G 19/01; A47G 19/2227

(57) **CLAIM**

The ornamental design for a cup, as shown and described.

DESCRIPTION

FIG. 1 is a perspective view of a cup showing the claimed design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof;

FIG. 7 is a left side view thereof; and,

FIG. 8 is an exploded view of the claimed design.

The broken lines illustrate portions of the cup that form no part of the claimed design.

1 Claim, 8 Drawing Sheets
